UNITED STATES PATENT OFFICE.

EDWARD PINCUS, OF PHILADELPHIA, PENNSYLVANIA.

DESIGN FOR A FLAG-HOLDER.

SPECIFICATION forming part of Design No. 29,229, dated August 16, 1898.

Application filed July 23, 1898. Serial No. 686,740. Term of patent 7 years.

To all whom it may concern:

Be it known that I, EDWARD PINCUS, a citizen of the United States of America, residing in the city and county of Philadelphia and 5 State of Pennsylvania, have invented and produced a new and original Design for Flag-Holders, of which the following is a specification, reference being had to the accompanying drawings, forming part thereof.

10 Figure 1 is a rear elevation of a flag-holder, showing my new design. Fig. 2 is a plan thereof.

15 The leading feature of my design consists of a body A in the form of an eagle with out-spread wings bearing flag-supporting mem-

bers. These members, as shown in the drawings, comprise a series of perforated lugs or projections B B, relatively disposed or arranged on the back of the wings. Below the perforated lugs are other lugs B', between 20 which is a depending basal portion C, provided with clamping-arms D.

I claim—

The design for a flag-holder, substantially as herein shown and described.

EDWARD PINCUS.
